UNITED STATES PATENT OFFICE.

IVAR DROLSHAMMER, OF DRAMMEN, NORWAY.

COMPRESSED-AIR BRAKE FOR RAILWAY TRAINS AND THE LIKE.

Application filed August 22, 1923. Serial No. 658,791.

To all whom it may concern:

Be it known that I, IVAR DROLSHAMMER, a citizen of Norway, and resident of Drammen, Norway, have invented certain new and useful Improvements in Compressed-Air Brakes for Railway Trains and the like, of which the following is a specification.

The leading idea of Patent No. 1,401,325, to regulate proportionally the pressure 10 stages of air brakes as well on pulling the brake as on releasing is here accomplished by means of slide valves; these have also proved to be useful throughout in form of ground-in piston-slides, by which an absolutely exact regulation is obtained. The peculiarity of such slides to show little leakage in working, has normally no influence, as the entire device is inexhaustible in so far as losses of pressure are continually 20 replenished from the main-supply-pipe, the supply of compressed air being thus independent of the supply by the auxiliary air-reservoir.

The invention is based on the perception 25 that these leakages of such compressed-air-brakes may attain a certain influence, in the case of a fracture of couplings and in connection therewith the interruption of the supply of compressed air by the main-pipe. In 30 this case however the working of such brakes is entirely dependent on the quantity of compressed air in the auxiliary reservoir. This reservoir however may be exhausted by leakages of the control-elements, and the 35 special idea of this invention is to remedy this exceptional case. To that end the control-apparatus is constructed in a way that it—in the ultimate position, corresponding to the absolute exhaustion of compressed air 40 in the main-pipe—cuts off a second time the air-exhaust of the brake-cylinder. This is achieved properly by valves which press against each other, and in the best manner by soft packings. So in normal working 45 all advantages of the control by slides are guaranteed, while for the mentioned exceptional case the troubles caused by the characteristics of the controlling elements are removed.

50 To accomplish this cutting-off-the-exhaust it is necessary to close all ways by which air may escape within the apparatus itself, so that two or even three places are to be tightened. To secure the proper work-

ing of these tightening-places, there is a 55 special method used—according to this invention.

The invention is shown in two constructions (Fig. 1 and Fig. 2), both longitudinal sections through the pressure-controller of 60 compressed-air-brakes.

The control-piston 10 is within the coil of the double-spring 11 connected to the rod 12 and the spring-holder 13. Along the piston-rod 14 moves the slide-valve 15, which is 65 supported by spring 16 against the piston 10. The slide-valve 15 regulates the supply of compressed air from the auxiliary reservoir, which enters the brake-cylinder from the channel 27 through cock 35 and the channel 17. The function of the brake corresponds generally to that of the the well-known "Drolshammer" system. The exhaust of compressed air from the brake-cylinder is effected by the small channels 70 18, 18 parallel to the axis of the cylinder and by the transverse borings 20, 20, which 75 are held free in the "down"-position (shown in the figures) by the slide-valve 15. Connected with the slide-valve is plate 21, which 80 holds the packing 22 in a groove. Normally this plate 21 with the packing 22 is removed so far from the mouths of the channels 18, 18, that the exhaust of the brake-cylinder is able to escape by streaming through the 85 channels 18, 18 round plate 22 and through the space between plate 22 and the partition-plate 23 to the exhaust 24.

A second packing 26 is attached to the rod 14 by means of plate 25. In the "up"-position 90 the packing 26 presses against the partition-plate 23, thus closing the central opening in the partition-plate 23.

If f. e. part of the train breaks off, the slide 10 moves into the "up"-position, dotted in the drawings, in consequence of the withdrawal of pressure, closing the opening in the partition-plate 23 by means of the packing 26. The slide-valve 15 begins now 95 its regulating work of supplying the brake-cylinder with compressed air, thereby effecting the maximum of braking-power in the brake-cylinder and always admitting air by a counter-movement from the auxiliary reservoir through pipe 27, if the maximum pressure in the cylinder decreases by small leakages. If, however, the auxiliary reservoir 100 is so far exhausted, that it is no longer

able to refill the brake-cylinder to the maximum of pressure, this counter-pressure cannot balance the pressure of spring 16, so that the slide-valve 15 moves into its "up" position, thereby bringing the packing 21 into effect. This may be supported and also its earlier movement effected by exhaust-air, escaping through the channels 18, 18, and causing a pressure in the space between the cylinder 19 and the partition-plate 23 because of the prevention of the exhaust-air from escaping through the rod-passage in the partition-plate 23, which is tightened by the packing 26.

To accomplish the solution of the problem of tightening, the piston 10 may be fitted with another packing that prevents the escape of compressed air along the piston 10. To this end the piston is fitted with a leather-collar 28, which normally (i. e. in the case of pressure above the piston) is pressed off the wall of the cylinder 19, so that the free movement of the piston is not interfered with. On strongly pulling the brakes the difference of pressure however inverts, because the pressure above the piston 10 nearly or totally ceases, so that the super-pressure now working from the interior of the cylinder presses the leather-collar 28 against the wall of the cylinder.

In the construction according to Fig. 2 the leather-collar is dispensed with by fitting the piston on both its passages out of the cylinder with packings in the form of valve-plates, by which the cylinder is closed. So the desired closing is effected by a simple method of pressing the packings against each other, while the free movement of the piston in its intermediate positions is not interfered with. The two valve-plates being attached to the same rigid object on the openings for the piston-rod, there exist two conditions of support, i. e. it is doubtful which of the valve-plates presses on its seat as the distribution of pressure in the cylinder cannot be predicted.

This special problem is solved by connecting one of the two valve-plates elastically with the piston-rod by means of a spring which is placed in a determinated relation to the piston-spring. By these means the yielding valve-plate closes first the respective passage while after still more pressure exerted on its spring by the spring 11 of the piston, the other valve-plate is also brought into the desired position, the distribution of pressure being always balanced thereby. In principle the construction of the brake, according to Fig. 1 is the same as in Fig. 2. The difference is, that in the design Fig. 2 the longitudinal borings 18, 18 in the cylinder 19 are replaced by simple transversal borings 18', 18' in the slide valve 15 opening below the cylinder 19. At the 65 passage of the piston-rod 12, the valve-plate

31 in form of a leather-packing is supported by a screwed-on cap 33, while at the opposite passage of the rod 14 the partition-plate 23 is constructed as an annular valve-seat. The rod 14 is connected with the valve-plate 25, 70 which bears the leather-ring 26 by the spring 30. The cap 32 fastening the leather-packing 26 to the valve-plate 25 forms the valve-guard for the valve-plate, relative to the rod 14, touching the end of this rod. 75

The piston 10 moving up, corresponding to a decrease of the air-pressure in the main-pipe according to the maximum of the braking-effect, f. e. in case of damage to the main-pipe the plate 26 presses first of all against the annular valve-seat 23, thus closing the exhaust, causing air-pressure against the free end of the slide-valve 15, whereby it is balanced and pressed upwards by the released power of spring 16, thus connecting the auxiliary reservoir with the brake-cylinder. The slide-valve 15 being closely pressed against the end of the cylinder 19 and tightened by the packing 22, the slide-spring 16 presses the piston-rod 14 90 down, because the spring power is no longer balanced by the pressure in the brake-cylinder, resulting in the pressing up of the piston because of the closing of the exhaust.

The cap 32, forming the valve-guard for 95 plates 25 or 26, surrounding the rod 14, has still another destination. The pressure in the brake-cylinder passing into the cap cannot escape, as the cap is closed all round; only the interior is set under pressure. So 100 the solution of the otherwise difficult problem of tightening the movable plate 25 to the rod 14 may be dispensed with.

Claims.

1. Control-valve for air-brakes, by which 105 besides the normal tightening by means of slides, effective during the full stroke of the control-elements under the pressure-conditions corresponding to the maximum of brake-power, an auxiliary closing of the exhaust of the cylinder is effected, so that in this case two tightening-elements are joined up in series.

2. Control-valve according to claim 1, in 115 which the auxiliary tightening of the exhaust in the ultimate position of the piston is effected by compression of tightening-elements in form of valve-plates, so that the free movement of the control-elements during their stroke is not injured.

3. Control-valve according to claim 1, in 120 which the rod of the control-piston is connected with a plate bearing a packing-ring, that on escaping of the air-pressure and releasing of the piston-spring presses against the partition-plate, effecting the closure of the cylinder of the control-piston, so that its central aperture for the exhaust is closed.

4. Control-valve according to claim 1, by 125 which a second closing of the exhaust by 130

means of valve-plates is effected by the control-slide movable against the control-piston under the action of the spring.

5. Control-valve according to claim 1, by which besides the auxiliary tightening of the exhaust-side of the cylinder of the control-piston and control-valve such tightening is effected also on the opposite side thereof.

10 6. Control-valve according to claim 1, in which the control-piston closes both the front-openings of its cylinder in its ultimate position, a distinct distribution of tightening pressure is obtained by connecting the one valve-plate by a spring with the piston.

15 7. Control-valve according to claim 1, the power and the strain of the spring of the movable valve-plate and its valve guard being

so arranged, that at first the valve-plate closing the exhaust presses against its seat, while 20 under corresponding compression of its spring now the tightening at the other front-end of the cylinder of the control-piston and the control-slide is effected.

8. Control-valve according to claim 7, in 25 which the stop of the movable valve-plate is effected by a valve-guard in form of a closed cap, surrounding the abutment of the piston rod and supplementing the valve-plate, penetrated by the piston rod.

In testimony whereof I affix my signature.

IVAR DROLSHAMMER.
